UNITED STATES PATENT OFFICE

FELIX JOSEPH MARIE PRODHOMME, OF PARIS, FRANCE

AUTOMATIC APPARATUS FOR SHOP WINDOWS

Application filed September 16, 1930, Serial No. 432,301, and in France September 21, 1929.

The present invention has for object an automatic apparatus for shop windows and, generally speaking, this apparatus can be applied to installations for advertising and exhibiting purposes and for attractions for fairs.

As can be seen, articles in stores are always, with a few exceptions, presented to passers-by in the same manner, that is to say laid on glass plates or on accessories where they remain fixed, more or less within sight of eventual buyers who often, seeing them in an unsatisfactory manner, and always in the same position and in the same direction, do not immediately appreciate the advantages of the said articles.

This invention is adapted to remedy the above mentioned inconveniences and it has for object an apparatus receiving special movements of rotation giving to the shop windows where it will be in use an animation constituting for the clients an attraction which will incite them to stop longer and more frequently in front of shop windows and will allow the users of this apparatus, by the very fact of its arrangement specially devised for certain categories of articles, to put in show a greater number of objects, to continuously vary (owing to the continuous or intermittent circular movement, whether it be vertical, oblique or horizontal, but always slow, attributed according to its destination to each type of apparatus) the presentation of the said articles, whilst bringing them automatically nearer the public as they pass and showing them from different sides.

Concerning the displaying devices, up to this day, use has only been made of devices in the shape of round plates rotating horizontally flatwise, or of endless movable bands or aprons rotating obliquely or parallel to the floor of the shop window, passing sometimes above, sometimes underneath, this resulting in the serious inconvenience that light articles or articles of very small height can

only be placed on these bands or aprons, since it is indispensable to carefully secure them owing to the fact that, when passing underneath the floor of the shop window, they are up side down.

The apparatus forming the subject-matter of the present invention can be actuated as well by hand, as by any other rudimentary means (springs, counterweights, etc. . . .), but generally speaking by any source of power, the nature of which will be determined by the importance of the said apparatus and in relation to the total weight of the articles it will be adapted to support and of the greater or less space available for placing the apparatus supplying the power.

In the majority of cases, the said apparatus will be actuated by electricity.

This invention will be described herein-after, by way of example, with reference to the accompanying diagrammatic drawings, in which:

Fig. 1 is a front view of one form of the apparatus,

Figs. 2, 3, 4 and 5 show respectively enlarged elevational views partly in section of modified roller supports,

Fig. 6 is an end view of the apparatus as shown in Fig. 1, and

Fig. 7 is a plan view of the same apparatus.

The apparatus is constituted by six vertical frames 29 arranged in a rectangle on the floor 30 of the shop window, and connected by three horizontal cross members 31. On these frames are secured three horizontal circular endless rails 32, surrounding the six frames, the greatest length of these rails forming a straight line 33, and the ends 34 being curved for allowing to effect the turns.

The apparatus is started by a bevel gear 35 actuating a vertical shaft 36 secured to the frames and to the rail, at points 37 and 38, two toothed horizontal wheels 39 and 40 being mounted on the said shaft 36.

A second vertical shaft 41, similar to shaft 36

36, but without bevel gear, rigidly carries two toothed wheels 42 and 43.

The wheels 39 and 42 and the wheels 40 43 are respectively connected one to the other by a chain (or by a cable or belt, etc. . . .) 45 5 and 46.

On each of these chains are attached, at points 47—48, several rods 49 (ten in the example under consideration) extending from the upper rail to the lower rail.

10 These rods are connected to rollers 50 respectively running on the corresponding rails, and the same is true for the nine other rods.

15 On each of these rods, at points 47 and 48, or slightly below, are mounted yokes 15 adapted to support the shelves 16 on which are placed the articles displayed.

20 When the shaft 36 is started, the toothed wheels 39 and 40 drive the chains 45 and 46 which, in their turn, drive in their circular movement the ten rods 49 and with them the twenty shelves they support.

25 These twenty shelves successively pass, two by two, those at the top and those at the bottom, before the public standing in front of the shop window.

30 In addition to occupying less room in depth, this apparatus has, by its special arrangement, the advantage of allowing to see the displayed articles on all their sides, from the front, from the side, and from the back, each shelf showing the articles from one side, then from the opposite side.

35 The rails 32 can be grooved (Fig. 2), or they can be in the shape of a knife blade, or of a cable (Fig. 3), they can be suspended, in two parts, rail and guard rail, the roller running between the rails (Fig. 4), or suspended, also in two parts, the roller inside, 40 in the shape of a ball, with ball bearings inside (Fig. 5).

45 Although the invention has been described above only in its application to the manufacture of automatic apparatus and devices for shop windows, it is to be understood that it can be applied to the manufacture of systems of special installations based on the principles and mechanisms above mentioned, 50 adapted to be used for advertising purposes and for constituting attractions for fairs, or any other uses; the nature, details, shape and dimensions of the elements entering in the constitution of these various installations can 55 obviously be modified according to the destination of the said installations, without departing thereby from the principle of the invention.

60 Having thus fully described the invention what is claimed as new and desired to be secured by Letters Patent is:—

65 1. An automatic apparatus for shop windows for displaying articles to the public including a supporting frame, endless horizontal rails thereon, rollers on the rails, ver-

tical rods connected in a detachable manner to the rollers, article carrying supports suspended so that they project laterally from the rods, means mounted on the frame and connected to the rods causing the rods to move around the frame, and means for operating said moving means. 70

2. An automatic apparatus as claimed in claim 1, wherein the means mounted on the frame for moving the rods includes vertical 75 shafts, sprocket wheels mounted on the shafts, endless flexible elements operating about the sprocket wheels and having connected thereto at suitable spaced intervals the rods.

3. An automatic apparatus as claimed in 80 claim 1, wherein the support includes in combination with the floor of a shop window, a plurality of vertical members and transverse cross bars arranged at the upper ends thereof, and wherein the rails are connected 85 on the outer sides of the vertical members near the top and bottom and at the middle thereof.

85 The foregoing specification of my "Automatic apparatus for shop windows" signed 90 by me this 3rd day of September 1930.
